UNITED STATES PATENT OFFICE.

ALBERTUS A. LONGMAN, OF DAYTON, OHIO, ASSIGNOR TO THOMAS J. FARRELL, OF SAME PLACE, AND WILLIAM BOTT AND JOSEPH BOTT, OF COLUMBUS, OHIO.

DESIGN FOR A LEVER.

SPECIFICATION forming part of Design No. 30,239, dated February 21, 1899.

Application filed January 28, 1899. Serial No. 703,753. Term of patent 14 years.

To all whom it may concern:

Be it known that I, ALBERTUS A. LONGMAN, a citizen of the United States, residing at Dayton, in the county of Montgomery and State 5 of Ohio, have invented and produced a new and original Design for a Lever, of which the following is a specification, reference being had to the accompanying drawings, forming part thereof, and in which like characters refer to correspondingly-formed parts.

My invention relates to a design for a lever for use more especially in game-tables.

Figure 1 is a side elevation view of a lever embodying my new and useful design. Fig. 15 2 is a top plan view thereof, and Fig. 3 is an end elevation view thereof, these three views being deemed essential to fully illustrate my new and useful design.

The horizontal bar A is provided on one end 20 with a vertical cylindrical extension B, whose top terminates in a plane C at an angle to the

length of the horizontal bar A. Intermediate its ends and at right angles with its length said horizontal bar A is provided with a bearing D.

The essential feature of my design for a lever consists of a bar provided with a bearing intermediate its ends and a cylindrical vertical extension on one end thereof, the top of said cylindrical projection forming a plane at 30 an angle with a straight line drawn between the ends of said bar.

What I claim is—

The design for a lever, substantially as shown and described.

In witness whereof I have hereunto set my hand this 18th day of January, 1899.

ALBERTUS A. LONGMAN.
